UNITED STATES PATENT OFFICE.

JOHN A. SPERRY, OF MUNNSVILLE, NEW YORK.

MOLDING FLASK.

Application filed April 18, 1923. Serial No. 632,946.

To all whom it may concern:

Be it known that I, JOHN A. SPERRY, of Munnsville, county of Madison, and State of New York, have invented certain new and 5 useful Improvements in a Molding Flask, of which the following is a specification.

This invention relates to molding flasks, and more particularly to flasks adapted for manual manipulation.

10 The prime object of the invention is to provide a flask, such that it may be removed from the mold with the expenditure of a minimum of time and labor upon the part of the operator.

15 Another object of the invention is to provide a flask of the above character, with improved means for freeing itself from the mold.

Another object of the invention is to provide improved means for retaining in the cope that part of the mold formed therein, while the cope is being manipulated to position it upon the drag after the pattern drawing operation.

25 A further object of the invention is to provide a flask which can be freed from the mold without danger of disturbing the block of sand constituting the mold, and whereby no entrance is made into the mold, such as 30 are made by devices now employed to hold the sand block formed in the cope during the handling of the latter to position it upon the drag.

A still further object of the invention is 35 to provide a strong durable flask, capable of withstanding without injury or impairment of efficiency, the rough usage or handling to which these devices are ordinarily subjected, which eliminates several objectionable features present in flasks of this character as hitherto constructed, and which may 40 be manipulated with a great saving of both time and labor.

Other objects and aims of the invention, 45 more or less specific than those referred to above, will be in part obvious and in part pointed out in the course of the following

description of the elements, combinations, arrangements of parts and applications of principles, constituting the invention; and 50 the scope of protection contemplated will be indicated in the appended claims.

In the accompanying drawing, wherein 55 there is illustrated a preferred form of embodiment of my invention:

Figure 1 is a side elevational view of my 60 improved flask, showing the parts in position to remove the flask from the mold, the normal position of certain of the parts being indicated in dotted lines.

Figure 2 is a top plan view of Figure 1.

Figure 3 is an end elevational view with 65 the parts in the position illustrated in Fig. 1, parts of the end members of the flask being broken away better to illustrate the construction; and

Figure 4 is an end view of my improved 70 flask, showing the way in which the same is operated to free itself from the mold, parts of the side walls of the flask being broken away.

Before proceeding to describe the details 75 of construction of my improved flask, it may here be noted that a considerable factor of the cost of sand castings resides in the labor cost expended in the formation of the sand molds. It is a well known fact that great losses are entailed by careless manipulation of the cope in positioning it upon the drag, whereby the sand is displaced and the 80 quality of the castings impaired, or the castings destroyed. Moreover, in the art of casting it has heretofore been necessary to employ skilled labor in the operation of forming the molds, thereby increasing the 85 cost of the castings. I aim by my present invention to decrease the cost of hand-casting production, by producing a flask which can be operated by unskilled laborers or workmen, and which is of such construction 90 that certainty of perfect casting production is assured, insofar as the formation of the molds is concerned.

Referring now to the drawings, wherein

similar reference characters refer to similar parts, the reference numeral 1 indicates the cope, and 2 the drag, the two parts constituting the flask. Each of these parts is 5 formed by side and end walls firmly secured together as by means of the metal straps 3, to provide substantially rectangular boxes adapted to be associated in the manner illustrated in the drawings with 10 the cope positioned upon the drag in such a position that the inner surfaces of the end and side walls will be in exact registry. The side and end walls of both the cope and drag are inclined slightly inwardly from 15 the vertical, as is usual in flask construction, whereby the latter may be more easily freed from the sand block.

The side and end walls of the cope 1 upon their inner surfaces are provided with a 20 plurality of relatively shallow surfaces, the purpose of which will be hereinafter explained.

Cope and drag have co-operating means whereby they may be placed together in the 25 position shown in the drawings with great exactness, whereby the outlines or edges of the mold formed in the respective parts will lie in exact registry. This means in the present instance, and which forms no part of my 30 present invention, comprises tapered pins 5 and 6 carried upon the flanges 7 and 8 upon angle-irons 9 and 10 fastened upon the opposite side members of the drag, as by means of the screws 11. In the present instance 35 the pins 5 and 6 are provided with threaded extensions which pass through apertures formed in the flanges 7 and 8 and are fastened to said flanges as by means of the nuts 12, threaded upon said extensions.

The side walls of the cope are likewise 40 provided with angle-irons 13 and 14, having the flanges 15 and 16 in which are formed tapered apertures 17 and 18, the walls of which are inclined to correspond with the 45 taper of the pins 5 and 6 so that when the cope is placed upon the drag, as shown, the aforesaid perfect registry of the inner walls of the cope and drag, and of the marginal portions of the molds, is assured.

The reference numeral 19 indicates the 50 presser board of the cope, and 20 the presser board of the drag. These presser boards, as is well known in the art, are employed in the molding machine to squeeze or press the sand tightly, respectively, into the cope and drag, and it will be noted that the thicknesses of the presser boards 19 and 20 are such that after the squeezing operation, the 55 upper and lower surfaces of both presser boards are located above and below respectively, of the corresponding ends of the cope and drag.

The reference numeral 21 indicates the 60 sand forming mold block, and 22 the mold which has been formed in the sand block,

one part 23 of the mold having been formed in the cope, and the other part 24 having been formed in the drag.

The construction thus far described, with the exception of the grooves 4 formed upon 70 the inner surfaces of the walls of the cope, is well known in this art; a description thereof, however, being deemed essential in order that my invention, which I shall now proceed to describe, may be more fully understood.

Briefly stated, my invention comprises a pair of devices mounted upon the cope, and operated by the hands of the operator when the latter is engaged in lifting the flask from 80 the mold, means being provided for holding the presser board of the cope stationary during the initial upward movement of the flask when lifted by the operator, whereby the flask is lifted cleanly from the mold without in anywise disturbing the latter. This means two of these devices are provided upon each cope, one on either side adapted and arranged for simultaneous manipulation by the operator, one device being located 90 near the forward end of one side of the cope, and the other upon the opposite rearward side thereof, the parts being oppositely disposed. Inasmuch as these devices are of identical construction, but one thereof need 95 be described.

Referring now to the device upon the righthand side, the reference numeral 25 indicates a lever, pivotally mounted upon a screw or bolt 26, carried upon the strap 3' 100 of the cope. This lever extends inwardly substantially parallel for a part of its length with the side wall of the cope, indicated at 27, whence it extends outwardly as at 28, at an angle, whence it extends inwardly as 105 at 29, which latter part is substantially parallel with the side wall of the cope. This outer part 29 forms a handle, and is located adjacent and above the flange 8 of the drag, which latter part, as will hereinafter be described, forms a finger or hand-hold for the operator of the flask, the dotted line 30 showing the manner in which the lower surface of this flange 8 is formed, whereby it may be 110 more readily grasped by the operator.

Pivoted, as at 31, upon the part 27 of the lever 25, is a rod 32, the upper end of which is provided with an inwardly formed extension 33, which when the parts are in the position shown in the full lines 115 of each figure of the drawing, overlies the presser board 19 of the cope. The rod 32, its lateral extension 33, and the lever 25, when these parts are in normal position, 120 occupy the positions shown in the dotted lines of Fig. 1 of the drawings, in which position the lateral extension 33 is received underneath a catch or shoulder 34, formed upon the end wall of the cope, a recess 35 being formed in the end wall of the cope 125 130

at its upper end to receive said part. The catch 34 may be conveniently formed by the metal straps 36 and 37, which are attached to the upper ends of the side and end

5 pieces of the cope, the recess 35 being formed by cutting away a portion of the end and side wall of the cope directly beneath the catch 35 of these metal straps, which has its end 38 slightly depressed to form a 10 point over which passes the extension 33 of the rod 32.

Positioned about the screw or bolt 31 which pivotally connects the rod 32 with the lever 25 is a spring 39, the end 40 of 15 which engages with the lever 25 and the opposite end 41 with a rearward extension 42 of the rod 32. The tendency of this spring is to swing said rod and the lever 25 to the positions shown in the full lines 20 of the drawings; the uppermost position of the lever, and consequently the position of the rod, being determined by the engagement of said lever with a strap 43, which is formed by a strap extending between a 25 fixed point 44 and the strap iron 3'. This strap 43 performs the triple function of a stop for the upward movement of the lever 25, as a guide for the rod 32, and as a reinforcing member for that part of the cope 30 upon which is mounted the above described device.

The strap 43 is held spaced from the side of the cope by means of the boss 45 and the spacer member 46. Having described my improved device, I shall now proceed to describe the operation thereof. At this point it will be noted that when the sand has been pressed into the cope by the squeezing operation, portions 46 of 40 the sand have been forced into the grooves 4, and these integrally formed portions or ribs of the sand block projecting into the grooves or recesses 4, serve to hold the sand block in the cope during its handling to 45 invert it and mount it upon the drag.

It will be understood that when the devices are not in use, the parts occupy the positions shown in the dotted lines of Fig. 1, in which construction the extension 33 is 50 received underneath the catch 34, the lever 25 being in its lowermost position. The parts are held in this position by the engagement of the extension 33 of the lever, and the catch 34. In operating the device the 55 handle 25 is lifted by the operator, whereupon the extension 33 of the lever 32 is forced out of its recess and over the point 38 of the catch 34, whereupon the operation of the spring 39 will swing the lever 32 to 60 the position shown in the full lines of the drawing, said rod 32 being of sufficient length to let the extension 33 clear the edge of the presser board 19. The upward movement of the lever 25 is arrested by its 65 engagement with the strap 43. The opera-

tor then depresses the handle 29 of the lever 25 with the palm of his hand, and inserts and catches the tips of his fingers underneath the flange 8.

This operation has carried the extension 70 33 and the lever into engagement with the presser board. The operator thereupon contracts his hand to force the lever 25 downwardly, and at the same time lifts the entire flask by means of his fingers, which are in 75 engagement with the flange 8, whereby the extension 33, which may be termed a "presser member", through the presser board 19, holds the sand block stationary on the presser board 20 of the cope, whereupon a 80 slight upward movement of the flask shears off the ribs of sand 46 from the sand block, whereupon the entire flask may be readily lifted from the mold.

It will be noted, due to the inclined surfaces of the inner wall of the flask, but a slight movement is necessary to affect this shearing action, as will be seen from an inspection of Fig. 4 of the drawings.

The cope and drag are then disengaged 85 and the parts whose operation is next above described, are returned to the position shown in the dotted lines of Fig. 1. This operation is effected by merely swinging the rod 32 rearwardly and causing the extension 90 or presser member 33 to again engage with the catch 34.

It will accordingly be seen that I have provided a construction well adapted to 100 attain, among others, all the ends and objects above pointed out in an exceedingly simple manner. The use of my improved device greatly facilitates disengagement of the flask from the mold, and such disengagement is effected by without in any way 105 disturbing the sand mold, the surfaces of the mold being free and clear from any ridges or grooves usually formed by movable devices extending inwardly from the cope for effecting the locking operation between 110 the cope and the sand block.

Having thus described my invention what I claim as new and desire to secure by Letters Patent is:

1. In a device of the class described, the 115 combination with a flask comprising two or more parts, and means carried by one of said parts for holding the mold stationary when the flask is being drawn therefrom.

2. In a device of the class described, the 120 combination with a flask comprising one or more parts, and means for pressing the mold downwardly when the flask is lifted therefrom.

3. In a device of the class described, the 125 combination with a flask comprising one or more parts, and means manipulated by the hands of the operator for pressing the mold downwardly when the flask is lifted therefrom.

4. In a device of the class described, the combination with a flask comprising one or more parts, and means for manually effecting a slight relative movement between the 5 mold and the flask at the instant the flask is lifted from the mold.
5. In a device of the class described, the combination with a flask comprising two or more parts including a cope and its presser 10 board, and means carried by the cope and engaging the presser board for exerting pressure therein when the flask is moved relatively to the mold.
6. In a device of the class described, the 15 combination with a flask comprising two or more parts including a cope and its presser board, and means carried by the cope and engaging the presser board adapted to be manually operated for exerting pressure 20 therein when the flask is moved relatively to the mold.
7. In a device of the class described, the combination with a flask comprising two or more parts, including a cope, said cope and 25 its sand block having mutually engaging parts, and means carried by the cope for severing one set of said mutually engaging parts simultaneously with the operation of lifting the flask from the mold.
8. In a device of the class described, the combination with a flask having a plurality of parts including a cope and its presser board, and a device mounted upon the cope 30 for exerting pressure upon said presser board in a direction contrary to the movement of the flask when it is removed from the mold.
9. In a device of the class described, the combination with a flask having a plurality 40 of parts including a cope and its presser board, and a plurality of devices mounted upon the cope for exerting pressure upon said presser board in a direction contrary to the movement of the flask when it is removed from the mold.
10. In a device of the class described, the combination with a flask having a plurality of parts including a cope and its presser board, and a plurality of devices engaged 50 and operated by the hands of the operator mounted upon the cope for exerting pressure upon said presser board in a direction contrary to the movement of the flask when it is removed from the mold.
11. In a device of the class described, the combination of a flask comprising two or more parts, including a cope, and means mounted upon the cope for exerting pressure upon the mold while the flask is being removed therefrom.
12. In a device of the class described, in combination, a flask comprising a plurality of parts including a cope and a drag, and co-operating means upon the cope and drag 65 for lifting the flask from the mold, and at the same time holding the mold stationary at the instant of the beginning of the flask lifting operation.
13. In a device of the class described, the combination with a flask, comprising two or 70 more parts including a cope, said cope having a plurality of recesses in its inner surface for receiving portions of that part of the mold enclosed therein, and means provided upon the cope for pressing upon the 75 mold when the flask is lifted, whereby said portions of the sand received in its recesses are sheared off when the flask is lifted.
14. In a device of the class described, in combination, a flask comprising a plurality of parts including a cope, the inner surface of said cope being provided with a plurality of recesses adapted to receive projecting portions of the sand block, whereby the latter is locked in the cope, and means whereby said projecting portions of the sand block are sheared off to free the sand block when the flask is removed from the mold.
15. In a device of the class described, in combination, a flask comprising a plurality of parts including a cope and a drag, said cope being provided with a presser board, oppositely disposed handles provided upon the drag, a plurality of presser members carried by the cope adapted to be moved in position above said presser board, and operative means for said presser members located adjacent the handles of said drag adapted to be engaged by the hands of the operator when lifting the drag to cause said presser members to engage with said presser board.
16. In a device of the class described, the combination with a flask comprising two or more parts including a drag and a cope, a presser board for said cope, a lever pivoted to said cope, a rod pivoted to said lever, having a presser member, means whereby said rod and its presser member are held in inoperative position upon said cope, means whereby said rod may be moved to carry said presser member above said presser board, and said lever being adapted to be operated when the flask is lifted, to move said rod, whereby its presser member is carried into engagement with said presser board.
17. In a device of the class described, the combination with a flask comprising two or more parts including a cope and a drag, a presser board for said cope, a plurality of levers pivoted upon opposite sides of the cope, a rod pivoted to each of said levers, each of said rods being provided with a lateral extension, means upon said cope for holding said rods and their lateral extensions in inoperative positions, means for moving said rods and their lateral extensions into operative positions above said cope, a presser board adapted to rest upon the mold above said cope, handles

provided upon said drag for lifting the flask, said cope being provided with a plurality of recesses in its inner wall adapted to receive portions of the mold located therein, thereby locking within the cope a portion of said mold, said levers upon the cope and said handles upon the drag being adapted to be engaged by the hands of the opera-

tor when lifting the flask to cause said lateral extensions of said rods to engage with 10 the presser board of the cope and press the latter downwardly when the flask is lifted from the mold.

In testimony whereof, I affix my signature.

JOHN A. SPERRY.
